ABRASIVE CLEANING SYSTEM

Gilbert D. Dill, South Bend, Ind., assignor to
 American Wheelabrator & Equipment Corpora-
 tion, a corporation of Delaware

Application December 29, 1945, Serial No. 637,923

6 Claims. (Cl. 51—9)

1

The invention relates to sheet blasting or cleaning equipment and, more particularly, to blast cleaning skelp preparatory to welding into pipe.

Among the general objects of the invention are to provide for adjustment of the several blast wheels with respect to the skelp strip; to provide a roomy cabinet which is subject to decreased blasting intensity and which gives additional room for workmen to inspect and repair equipment; to provide an improved lining for the cabinet; to protect the blasting units from flying abrasive; to seal the removable units with respect to the cabinet; to provide an improved guide path for the work strip through the machine; to provide for handling different widths of strip; to insure removal of abrasive from the skelp before leaving the machine; to provide equalization between the several abrasive circulatory systems in case one system becomes over-supplied at the expense of another; to clean skelp more efficiently.

According to a preferred form of the invention, the cleaning machine comprises a large roomy cabinet having a removable clapboard lining on longitudinal side walls, end walls and roof. The clapboard lining may comprise removable plates suitably hung in position so that they may be easily removed and replaced. A suitable longitudinal rail or skid connects the entrance and exit of the cabinet over which the skelp slides. Adjustable manganese steel side guides are provided to laterally guide the skelp strip through the machine. The blasting units are located under the skelp strip and may be arranged in pairs for cleaning opposite margins on the under surface of the skelp strip. Each unit may comprise a platform or car on which the blasting wheel is journaled and a motor located for driving the blast wheel. A protecting shroud surrounds the motor and top of the car, having close fitting engagement with the longitudinal side wall of the cabinet. Transversely extending tracks are provided for each unit whereby the units may be removed laterally from the machine for quick replacement with a spare. Suitable screw jack adjusting devices may be provided for adjusting the position of each unit with respect to the skelp strip and a suitable clamping device may be provided for holding the blasting unit in adjusted position. Each pair of blast wheels may have its own circulatory system for recovering the spent abrasive, cleaning and sizing it and returning it to position for feeding the blast wheels. Equalizer pipes may connect the storage hoppers of the several systems with the receiv-

2

ing hoppers to equalize disposition of the abrasive.

The invention also consists in certain new and original features and combinations hereinafter set forth and claimed.

5 Although the novel features which are believed to be characteristic of this invention will be particularly pointed out in the claims appended hereto, the invention itself, as to its objects and advantages, and the manner in which 10 it may be carried out, may be better understood by referring to the following description taken in connection with the accompanying drawings forming a part hereof, in which:

Fig. 1 represents diagrammatically a bottom 15 view of a section of skelp going through the machine made up of four Wheelabrator units, the supports and guides for the skelp strip, and showing the margins cleaned by the wheels, said margins being indicated by stippling;

Fig. 2 is a general longitudinal elevation of the 20 whole machine;

Fig. 3 is a detail section taken along a plane 25 parallel to Fig. 2;

Fig. 4 is a transverse section taken on the line 25 4—4 of Fig. 3, illustrating the construction of the Wheelabrator car and its shroud having sealing relation with the cabinet to prevent ingress of air and egress of grit;

Fig. 5 is a detail showing the roof clapboard 30 plates and manner of hanging; and

Fig. 6 is a detail showing side clapboard plates 35 and manner of hanging.

In the following description and in the claims, various details will be identified by specific names 35 for convenience, but they are intended to be as generic in their application as the art will permit.

Like reference characters denote like parts in the several figures of the drawings.

In the drawings accompanying and forming 40 part of this specification, certain specific disclosure of the invention is made for purposes of explanation, but it will be understood that the details may be modified in various respects without departure from the broad aspect of the invention.

The machine according to the invention cleans 45 a band 11 (Fig. 1) on both margins of the under-side of a strip or sheet 10 of skelp used for making welded pipe. It is necessary to clean only one 50 surface of the strip, and only the margins thereof, for the welding operation. When the strip is bent to form the pipe, the electrodes engage the cleaned margins to butt-weld the seam. The edges of the strip are already clean from a prior cutting operation.

Referring to the diagram shown in Fig. 1, the marginal paths formed by the blast are indicated by 11, the blast wheels by 14, 15, 16 and 17; and the bottom skid and adjustable side supports for the strip are indicated by 40 and 31 respectively. The direction of strip travel is denoted by E.

Each blast unit is mounted upon a separate carriage or frame, with the plane of the wheel parallel to direction of strip travel. The blast units are adjustable and removable in a direction transverse to the direction of strip travel and from opposite sides of the machine, as indicated by arrows A, B, C and D. The blast units are arranged in pairs, each pair cleaning the opposite margins, and the units are removable in directions opposite the margin which the particular unit cleans. The number of pairs of cleaning units is determined by the speed at which it is desired to pass the strip through the machine, the higher the speed, the more pairs.

The installation in the form shown comprises in general (Fig. 2) a cabinet 12 having a roof 20, side walls 21 and 22, an entrance end wall 23, an exit end wall 24, and a grating floor 26 leading to two hoppers 27 and 28. Four cleaning units are shown, two of the units 14 and 16 being removable through one side wall 21 of the machine and two of the units 15 and 17 being removable through the other side 22 of the machine. The side walls have service doors 29, 30 and 36, 37, one opposite each blast unit and on the side opposite from which the unit is removable.

The cabinet 12 and hoppers 27, 28 are of knock-down welded construction to insure ease of handling in shipping and erection. They may be fabricated of steel plate of one-half inch in thickness, and have heavy structural steel reinforcing members where needed. The cabinet is very roomy to decrease intensity of rebounding blast on walls and is entirely lined with thick steel wearing plates forming a "clapboard" lining indicated generally by 25.

The entrance and exit points are sealed by rubber curtains 32 and 33 to seal the entrance and exit openings against escape of dust and abrasive. A vestibule 18 is provided at the exit end of the machine for the purpose of insuring a clean sheet or strip for further processing and to prevent loss of abrasive. Within the vestibule 18 are special flat air-blast spray nozzles 39 so arranged that both sides of the skelp stock are thoroughly cleaned of loose abrasive. These spray nozzles are supplied by a motor-driven high pressure centrifugal blower 38. The work 10 is propelled through the machine by external means, as for example, by pinch rolls 34, 35 at the entrance and exit ends of the machine as indicated.

The path for guiding and supporting the skelp strip 10 through the machine comprises a continuously extending steel skid or rail 40 whose upper surface is at substantially the same level as the lower walls 41 of the side guides 31. A series of vertical columns 42 having brackets 43 support both the central skid 40 and the cross bars 44 on which the cast manganese steel side guides 31 rest. A series of bolts 45 passing through suitably positioned holes in the cross bars 44 are provided to adjust the side guides on the cross bars 44 to handle different widths of skelp.

The clapboard lining 25 covers roof, ends and sides and has suitable openings for the passage of the skelp strip, for doors, blast units, cross bars and other members passing to or through the

outer walls of the cabinet. The clapboard lining comprises removable wear plates arranged in overlapping or clapboard fashion, which are held in place by hook constructions on the back side protected from the blast and eliminating bolts. This permits a wear plate to be removed and replaced simply by a workman going in, lifting off the old plate and hanging on a new one. The wear plates may weigh from eighty to one hundred pounds and be of one inch thick steel.

The roof plates, indicated in general by 46 in Fig. 5, have hooks 47 welded along one margin of the plate. These hooks are hung on depending brackets 48 welded to the roof wall of the cabinet. It will be noted that the hooks 47 are located near one edge of the plate and the other end of the liner plate rests upon the adjoining margin 49 of the next plate forming a lap joint at this point.

The assembly of side plates is indicated in Fig. 6, each side plate being indicated by 50. The side plates have angle clips 51 welded thereto engaging over angles 52 welded to the side walls 21, 22 or end walls 23, 24 of the cabinet. The wall angles 52 have openings 53 in the bottom thereof for reasons discussed hereinafter. The upper edges of the side plates 50 may form supports for adjacent roof plates 46, if desired, as indicated.

In both roof plates and side and end wall plates the adjoining liner plates in each row have butt joints; it is only the plates of adjoining rows that have lap joints; thus being similar to ordinary outdoor house roof shingles. In the vertical or upstanding walls the butt joints thus extend vertically and the lap joints extend in line horizontally.

It has been found that the clapboard construction withstands the action of the abrasive better than horizontal butt joints which have a tendency to permit the abrasive to wear grooves therein at the joints. The openings 53 in the side angles 52 permit the draining or dropping of the abrasive which may become lodged in the angles and thus reduces inactive abrasive.

The machine in the form shown is equipped with four up-blast blasting units so designed that each unit with its motor drive is self-contained and protected from abrasion and is adjustable through a distance at right angles to the direction of movement of the skelp strip. These units are mounted, two on each side of the cabinet, and may be easily removed and replaced with a spare unit in case of breakdown.

Since the several blast units are substantially alike, it is sufficient to describe one in detail. Each unit (Figs. 3 and 4) comprises a platform or frame 57 having suitable bearings for supporting flanged wheels 58. The flanged wheels 58 run on tracks 59 supported by I-beams. The platform 57 supports an electric motor 60 which drives the blast wheel through a belt 61, the blast wheel being mounted on a separate shaft 69.

The motor 60 is protected by a shroud 62 arched over the top of the unit and having sides 63 suitably secured to the platform 57. The shroud 62 has an end wall 64 through which the blast wheel projects. The blast wheel is located between the end wall 64 and an outer end wall 65 through which the funnel pipe 66 projects for feeding the center of the blast wheel with abrasive, as will be understood by those skilled in the art. The funnel pipe 66 has a funnel-shaped opening 67 fed by a flexible depending hose 68 which is removable from the funnel 67 when the

blast unit is removed from the machine. The curved hood 62 has tight fit with the respective side walls 21 or 22 of the cabinet to prevent exit of dust and abrasive.

The several blast units are each removable from the machine, as a unit, by being rolled out on tracks 59 through the wall which the shroud 62 engages, that is, the wall opposite to the particular blast wheel (see arrows A, B, C, D). For this purpose the tracks for each unit may be extended laterally. If desired, only one set of extension tracks 70 may be provided for all units, shiftable to the particular unit by an overhead crane (not shown) for removing any particular unit.

The unit 16 is indicated diagrammatically in Fig. 4 in removed position on extension tracks 70. This figure also illustrates the crane sling hooks 72, of which there are four for each car, two on each side, and by which the unit may be lifted by an overhead crane (not shown).

For closely adjusting the position of any blast unit, an adjustable screw is provided and for holding the blast unit in adjusted position, eccentric clamps are provided.

The adjusting screw comprises a screw threaded housing 75 (Fig. 4) rigidly mounted on two channels 73 forming part of the stationary framework of the cabinet. Mounted on the underside of the unit car are bearings which journal the screw 76. The screw has a shaft 77 with a non-circular end 78 for engagement by a suitable wrench (not shown) for turning the screw 76. The screw 76 engages housing 75 to adjust the car.

The blast unit clamping device comprises channel-shaped clamps 80, one or more on each side of the unit. Each clamp is mounted upon an eccentric cam 81 and the clamps have hooks 82 which engage over the lower flanges of the channel irons 14 forming part of the frame of the car. The eccentric 81 is mounted upon a shaft 83 suitably journaled in bearings 84 attached to the supporting track I-beams, which shaft has a handle 85 projecting out through the wall of the cabinet. By rotating the handle, the eccentric clamps 80 may be tightened to clamp or unclamp the channel irons 14 to hold the car in position or to permit its removal.

It will be understood that the screw jacks 75, 76 are used to locate the car with its blast wheel in proper position with respect to the margin of the skelp strip it is desired to clean and is not intended to hold the cleaning unit in position. The eccentric clamps 80, on each side, fixedly hold the unit in position after it has been properly located by the screw jacks. Suitable gear and ratchet locks (not shown) may be provided for holding the eccentrics 81 in locked position.

It will be understood that the manner of feeding and circulating the abrasive may be similar to those now in use. The spent abrasive, after striking the work, falls down through the grating floor 26 into the several hoppers 27, 28. Each hopper may have its own complete circulating equipment including an elevator for elevating the abrasive; a separator for cleaning and sizing the abrasive; an overhead storage hopper 71; and feed pipe 68 extending from the storage hopper to the funnels 67 of the two blast units forming part of their particular circulatory system.

To prevent accidental acquisition of abrasive by one particular circulatory system at the expense of the other, cross-feed pipes 90 are provided. Each pipe connects a storage hopper 71

of one circulatory system to the receiving hopper 27 or 28 of the other system. This pipe is connected to such a point on the abrasive storage bin 71 that, when the abrasive in the storage bin builds above the level at which this equalizing pipe connects, the excess abrasive will flow down this pipe into the other circulatory system.

Thus blasting and cleaning equipment is provided, which will efficiently clean the margins of

- 10 skelp at a high rate of speed, depending upon the number of pairs of blasting units. Each blasting unit is adjustable for different widths of stock and is removable for inspection, replacement and repair. Each unit is completely protected against flying abrasive and the unit is sealed with the cabinet at the points of removal. The clapboard or shingle type lining for roof and side walls effectively withstands wear due to flying abrasive and is easily removable and replaceable by simply unhooking each plate and replacing it with a new one. The central skid effectively guides the skelp through the machine, assisted by the adjustable manganese steel side guides which can handle different widths of stock. The special exit vestibule insures removal of any abrasive which might accidentally remain on the work, thus insuring that the abrasive will not be carried with the stock into further processing rolls.

- 20 25 30 35 While certain novel features of the invention have been disclosed herein, and are pointed out in the annexed claims, it will be understood that various omissions, substitutions and changes may be made by those skilled in the art without departing from the spirit of the invention.

What is claimed is:

1. In blast-treating apparatus, a cabinet having entrance and exit walls, a path for continuous strip or sheet stock including a central rail or skid extending substantially from entrance to exit, side guides having recesses to receive the edges of said strip, said side guides being laterally spaced from said central rail or skid, said side guides being spaced longitudinally from each other, whereby to expose said strip to the blast, and means for blasting said strip.
2. In an abrading apparatus, a cabinet having a roof, longitudinal side walls, an entrance end wall and an exit end wall, curtains in the entrance and exit end walls to seal openings for passage of strip or sheet stock, a path for the strip stock including a central rail or skid extending substantially from entrance opening to exit opening, cross bars below the level of said skid, U-shaped side guides adjustable on said cross bars receiving the edges of said strip, and means for abrading said strip.

3. In a cleaning apparatus, a cabinet having a roof, longitudinal side walls, a path to carry a strip through the machine, a blast unit comprising a car, a blast wheel journaled on said car, a motor on said car and driving said blast wheel, tracks for said car extending transversely of the length of said cabinet, means for adjusting said unit on said tracks to locate the blast wheel in proper relation to the strip, a shroud on said car surrounding the motor and blast wheel shaft, said shroud fitting the adjacent longitudinal side wall.

4. In a cleaning apparatus, a cabinet having a roof, longitudinal side walls, and entrance and exit end walls, a path extending between said entrance and exit walls to carry a skelp strip through the machine, a plurality of blast units under said path, each unit comprising a car, a blast wheel

journaled on said car, a motor driving said blast wheel, tracks for said car extending transversely of the length of said cabinet, means for adjusting said units on said tracks to locate the blast wheels in proper relation to the margin of the skelp strip, and means for clamping said removable units in adjusted position, said units being removable through side walls remote from the blast wheels, each unit having a shroud surrounding the motor and blast wheel shaft, said shroud fitting the adjacent longitudinal side wall, and being open to the outside of the cabinet.

5. In blasting apparatus, a plurality of blasting sets, each set comprising at least one blasting machine, a separate circulatory system for each set for recovering spent blast material, transferring it to its storage tank and feeding it to its set, means connecting said systems to convey excess blast material from one system to another, and means for housing said blasting machines to contain flying blast material.

6. In blast apparatus, two blasting sets, each set comprising at least one blasting machine, a separate circulatory system for each set, each

system comprising a hopper under its set for recovering spent blast material, a storage tank above said set, elevating means transferring blast material from said hopper to said tank, feed means connecting said tank and its set, equalizer pipes connected at predetermined points of the storage tank of each system with the hopper of the other system, and means for housing said blasting machines to contain flying blast material.
